UNITED STATES PATENT OFFICE

EJNAR CHRISTIANSEN, OF BIRMINGHAM, ENGLAND, ASSIGNOR OF ONE-HALF TO CARL OSCAR ERICSSON, OF BIRMINGHAM, ENGLAND

INTERMITTENT GEARING

Application filed April 12, 1926, Serial No. 101,444, and in Great Britain April 18, 1925

This invention comprises improvements in means for intermittently moving a revolving member and particularly relates to such means for use in machines for moulding pie-
5 casings or the like.

According to the present improvements, a revolving member or table is rotated by means of a pin on one revolving member engaging in a slot in the other revolving member and means are combined therewith for holding the member or table at the end of each intermittent movement, which comprise pins on one revolving member which are engaged by a part annular groove in the other revolving member. By these means a somewhat heavy and quickly operated table or member can be stopped and held stationary at the end of each intermittent movement with a minimum of wear or damage to the mechanism. The table which is intermittently revolved is also supported in the improved manner hereinafter described.

Referring to the drawings:

Figure 1 is a perspective view of a machine constructed according to this invention.

Figure 2 is a sectional plan of the box table, the section being taken on line $\alpha\alpha$ of Figure 3, α being the front of the machine.

30 Figure 3 is a section on line yy of Figure 2.
Figure 4 is a section on line zz of Figure 2.

Figure 5 is an underside view of the driving disc hereinafter referred to.

Figure 6 is a plan view of a detail herein-after referred to, and

35. Figure 7 is a side view of the machine looking in the direction of arrow B. Figure 1

According to a convenient embodiment of this invention, the moulding tool 1 is recip-

40 this invention, the moulding tool 1 is reciprocated through the medium of a driving shaft 32 carrying the fly wheel 25 which is

shaft 32 carrying the fly wheel 25 which is geared to an electric motor 2 or any other convenient source of power. The moulding

convenient source of power. The moulding or other tool is operated by the said driving crank shaft 22 so that the moulding tool

45 crank shaft 32 so that the moulding tool is operated every rotation. The electric motor 2 drives a shaft 26 by means of the belt 27.

2 drives a shaft 26 by means of chain transmission 27, and such shaft transmits the drive to the mid-driven shaft 28.

drive to the said driving shaft carrying the fly wheel 25 through the medium of worm

28 and worm wheel 29. A stationary box ta-

ble 3 is carried by the machine frame, and such box table carries a revolving table 4. This revolving table has a central spindle 5 which passes through an inwardly directed boss 8 carried by the top wall of the box table 3, and the end of this spindle 5 located in the box table 3 carries a cast metal or other disc 6. The underside of the revolving table 4 is supported on spring pressed members or rollers 7 let into the top surface of the box table 3, such rollers 7 holding the revolving table 4 from the box table and maintaining the said cast metal disc 6 against, preferably, ball bearings located between such disc and the end of the said inwardly directed boss 8, through which the said revolving table spindle passes. Each said spring pressed roller is conveniently mounted in a bifurcated member 9 which is slidably mounted in a tubular member 10 fixed in the top surface of the box table 3, a spiral spring 11 being located between the inner end of this tubular member and the bifurcated member. An annular groove is formed in the underside of the table 4 for receiving the spring pressed rollers 7.

The revolving table 4 may, for instance, be adapted to receive six moulds or tins 12, and is therefore required to be moved one sixth of a revolution for each stroke of the moulding tool 1. For this purpose six radial slots 13 are formed in the cast metal disc 6, and a pin or roller 14 on another revolving driving member 15 is adapted to enter one slot 13 and move the table 4 round one sixth of a revolution before leaving this slot 13. This latter revolving driving member 15 is carried on a spindle 16 mounted in an inwardly depending boss 17 in the box table 3, and comprises an arm 18 passing from one side of the spindle, the sides of which arm curve outwardly to form a sector 19 on the other side of the spindle. The driving pin or roller 14 is carried by the top surface of the said arm 18, and a groove 20 is formed in the said sector also on the top surface. Six pins or rollers 21 are mounted on the underside of the said cast metal member 6 intermediate the radial slots 13. When the revolving driving member 15 is rotated, the driving pin 14 engages

a radial slot 13 and moves the cast metal disc 6 one sixth of a revolution. As the pin 14 is leaving the slot 13 one of the said pins 21, intermediate the radial groove 13, enters the groove 20 in the sector portion 19 of this driving revolving member 15, and therefore locks the revolving table 4 against further movement. As the groove 20 in this sector leaves the pin 21, the driving pin 14 enters the next 10 succeeding radial slot 13. It will therefore be seen that the table 4 can only be moved an exact amount and is positively locked against rotation during the moulding operation and until the revolving table is again to be rotated. The driving member 15 is conveniently driven through the medium of a horizontal shaft 22 located in the box table 3 which is driven by chain 30, and chain wheel 31 from the shaft 26. The said horizontal 20 shaft 22 further transmits the drive by means of a worm 23 and a worm wheel 24. The box table 3 forms an oil box, thus providing for the mechanism to run in an oil bath. The bottom of the box table may form the top of 25 the pedestal 27.

Claims:

1. Means for intermittently moving a revolving table comprising a revolving driving member, a pin or roller carried thereby, a 30 spindle on which the revolving table is mounted, a stationary table for the machine in which the spindle is journaled, spring pressed anti-friction members for resiliently supporting the revolving table on the stationary table, a disc having radial slots mounted on the said spindle with which slots the said pin or roller engages and means for holding the revolving table in a predetermined position during the stationary period.
2. Means for intermittently moving a revolving table comprising a revolving driving member, a pin or roller carried thereby, a 35 spindle on which the revolving table is mounted, a stationary table for the machine in which the spindle is journaled, spring pressed plungers carrying anti-friction rollers and mounted in the said stationary table for bearing against the underside of the revolving table, a disc having radial slots 40 mounted on said spindle with which said slots in the pin or roller engage and means for holding the revolving table in a predetermined position during the stationary period.
3. Means for intermittently moving a revolving member comprising a horizontal revolving table, a stationary table on the upper side of which the revolving table is mounted and on the underside of which are located 45 the means for intermittently moving the revolving table, a spindle on which the revolving table is mounted and which passes through a boss depending from the stationary table, a disc having radial slots mounted 50 on said spindle on the underside of the sta-

tionary table, a driving member mounted on a spindle mounted on and depending from the underside of the stationary table, and carrying a pin or roller for engaging said slots, a tail piece on the driving member having a concentric groove for engaging pins or rollers carried by the said disc, and means for continuously revolving the driving member comprising a spindle carrying a worm, a member carrying the bearings for the last mentioned spindle fixed to the stationary table, a worm wheel on the said driving member, and a toothed wheel on the spindle carrying the worm.

In witness whereof I have signed this specification.

EJNAR CHRISTIANSEN.
